SuperHandy Pro ULV Garden Fogger Backpack Mist Sprayer, Cordless Battery, 2.6GAL, w/Upgraded Tank & Turbo Nozzle—For Lawn-care, Hydroponics & Disinfecting, available in Amazon.com, customer review oldest date May 7, 2021 [online], [site visited Feb. 6, 2024], Available from the internet URL: https://www.amazon.com/SuperHandy-Disinfectant-Cordless-Adjustable-Particle/dp/B091G2GW2T?ref=ast_sto_dp (Year: 2021).*

Primary Examiner — George J Ulsch

Assistant Examiner — Kathryn Elizabeth Zieno

(57) **CLAIM**

The ornamental design for a backpack sprayer as shown and described.

DESCRIPTION

FIG. 1 is a perspective view of a backpack sprayer showing our new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

The broken lines shown on the drawings depict portions of the backpack sprayer that form no part of the claimed design.
